UNITED STATES PATENT OFFICE

116,960

DESIGN FOR A DRESS

Marie V. Mascitelli, New York, N. Y.

Application September 11, 1939, Serial No. 87,112

Term of patent 3½ years

To all whom it may concern:

Be it known that I, Marie V. Mascitelli, a citizen of the United States, residing in New York city, in the county of New York and State of New York, have invented a new, original, and ornamental Design for a Dress, of which the following is a specification, reference being had to the accompanying drawings, forming part thereof.

Fig. 1 is a front view of a dress showing my design;

Fig. 2 is a rear view of Fig. 1, and
Fig. 3 is the side view thereof.

I claim:

The ornamental design for a dress, substantially as shown.
